[57] **ABSTRACT**

A corotron is disclosed herein in which the surrounding shield is coated with a photoconductive insulator. The extent to which the shield is grounded is controlled by the extent to which it is subjected to illumination. When the shield is illuminated and fully grounded, the corotron operates in the manner known to the prior art. When the corotron is in darkness and therefore not grounded because of the photoconductive insulator, charge accumulates on the shield causing the corona wire to stop emitting.

FIG. 2

EXPOSURE CONTROLLED CORONA DEVICE

BACKGROUND OF THE INVENTION

The present invention relates to the field of xerography and in particular to an improved corona generating device for imposing electrostatic charge on a xerographic surface.

In xerography, one known method by which a photoconductive surface, or photoreceptor, is sensitized is by the use of ions generated in a corona discharge. To effect the corona discharge, one or more corona wires is maintained at a high potential and the resultant electric field strength at the surface of the wire causes air molecules to become ionized. These ions are drawn to the xerographic plate by the difference in potential existing between wire and plate. The build-up of these ions on the plate creates a potential across the plate.

In general, a grounded shield is used in association with the corona wire so as to control and direct its discharge onto the photoreceptor.

Reference is hereby made to U. S. Pat. No. 2,836,725, issued to Robert G. Vyverberg, wherein corona generating devices of the type briefly described above are more fully disclosed.

One characteristic of corona generating devices, or corotrons as they have become known, is that the corona-emitting wire is maintained at a high voltage. If it is desired to switch this voltage on and off, elaborate and expensive switching apparatus would be required to handle this high voltage.

SUMMARY OF THE INVENTION

It is an object of the present invention to provide a shield for a corona generating apparatus, which shield is capable of controlling the level of emission from the corona wire.

Another object is to provide an optical means for switching a high voltage corona wire.

Briefly, this invention is practiced in one form by a grounded corotron shield which is lined with a photoconductive insulator. When illuminated, the photoconductive material becomes conductive and the shield is fully grounded. When not illuminated, the photoconductor is an insulator and the corona shield collects charge from the corona wire. When the shield becomes charged to a potential near that of the wire, the wire ceases to emit and thus the corotron is switched off.

For a better understanding of this invention, reference is made to the following detailed description given in connection with the accompanying drawing.

FIG. 1 is a somewhat schematic representation of a corotron shield member, all disclosed and adjacent shield in operative position relative to a charge plate.

FIG. 2 is a fragmentary detail showing the structure of a corotron shield according to this invention.

DESCRIPTION

Referring now to FIG. 1, there is shown the general environment in which the present invention is used. It includes a corotron generally indicated at 2 disposed relative to a xerographic photoreceptor 4. As is well known, the corotron 2 acts to ionize the adjacent air and the resulting ions flow in a corona current to the

corotron shield 6 and to the photoreceptor 4. Shield 6 is partly composed of a conductive material and is grounded. Photoreceptor 4 includes a conductive grounded plate 8 and a coating of photoconductive insulation 10. A corona wire 12 disposed within the shield 6 is maintained at a high voltage for the purpose of effecting the desired corona current. The foregoing is a brief summary of the prior art.

Referring now to FIG. 2, the structure of the corotron shield 6 of the present invention is shown in greater detail. The shield is shown only fragmentarily since its geometrical configuration is not material to this invention. Shield 6 is composed of a transparent outer material 14 with a conductive layer 16 on its inner surface. The conductive layer 16 is connected to ground. A photoconductive layer 18 is in turn applied to the conductive layer 16. A light source is schematically represented at 20 and positioned to illuminate the corotron shield 6.

One suitable material for the outer transparent material is NESA glass. The conductive layer 16 is either a transparent layer or semi-transparent, so as to permit illumination from source 20 to reach the photoconductive layer 18.

The operation of this corotron structure is as follows: When the shield is illuminated, the photoconductive layer 18 is conductive and the corotron shield 6 is therefore conductive and grounded in the usual manner. In the absence of light, the photoconductive layer 18 is an insulator so that charges emitted from the corotron wire 12 accumulate on the surface of layer 18. When the potential on the layer 18, that is to say on the inner surface of the corotron shield 6, reaches that of the corotron wire 12, the wire ceases to emit and the corotron is thereby switched off.

The intensity of light from source 20 determines the degree to which the photoconductive layer 18 is conductive (or insulative) and thus determines the degree to which the corotron emits. Additionally, the corotron and shield may be arranged so that the wire-to-shield spacing is less than the wire-to-plate spacing, permitting a greater measure of control by the shield over the corotron emission.

By the simple switching on and off of a light source, or the control of its intensity, the corotron of this invention is controllable as to current output level. This corotron shield obviates the necessity for expensive or intricate switching gear otherwise required for use with high voltages.

While the light source 20 has been schematically represented on the side of the shield 6 opposite that of the corona wire 12, it may of course be located on the same side of the shield.

The foregoing description of an embodiment of this invention is given of way of illustration and not of limitation. The concept and scope of the invention are limited only by the following claims and equivalents thereof which may occur to others skilled in the art.

What is claimed is:

1. A corona generating device including a corona emission electrode and a shield electrode operatively disposed relative to said emission electrode, said shield electrode including an electrically conductive member which is connected to ground and a photoconductive insulative member electrically connected to said conductive member and disposed between said conductive member and said emission electrode, and

means to illuminate said photoconductive insulative member to render the same conductive.

2. A corona generating device including a corona emission electrode and a shield electrode partially surrounding said emission electrode, said shield electrode including a grounded electrically conductive layer and a photoconductive insulative layer disposed on and electrically connected to said conductive layer on the emission-electrode side thereof, and a light source in

optical communication with said photoconductive insulative layer,

whereby corona charge emitting from said emission electrode to said shield electrode flows to ground when said insulative layer is illuminated and accumulates on said shield when said insulative layer is not illuminated.
